UNITED STATES PATENT OFFICE.

MICHAEL BOHN, OF NAGYKIKINDA, AUSTRIA-HUNGARY.

MACHINE FOR CLEANING AND SORTING CLAY OR THE LIKE.

1,031,832.

Specification of Letters Patent.

Patented July 9, 1912.

Application filed January 27, 1908. Serial No. 412,907.

To all whom it may concern:

Be it known that I, MICHAEL BOHN, a subject of the King of Austria-Hungary, residing at Nagykikinda, in Austria-Hungary, have invented certain new and useful Improvements in Machines for Cleaning and Sorting Clay or the Like, of which the following is a specification.

Devices for cleaning and sorting clay are well known which comprise a cylinder containing a mixing and conveying worm and having arranged in its walls perforated sieves with passage openings or meshes of different width through which the clay material is pressed out, while stones and coarse admixtures pass into the discharge portion of the cylinder forming a collecting chamber, and are discharged from the cylinder through an adjustable opening. In the working of these devices it has been found advisable to arrange the sieves or the like on both sides instead of in the well known one-sided arrangement, whereby the length of the device is reduced or its output increased, and the consumption of power reduced. Moreover, practical experience has shown that impurities, coarse admixtures, etc., did not leave the clay purifier through the opening in the bottom of the cylinder, but on the contrary partly remained in the collecting chamber. To avoid this disadvantage, the discharge portion of the cylinder is provided, according to this invention, with a connection branch, an opening or the like, to which can be attached any desired pump, for instance a well-known boiler test pump, by means of which a purifying liquid (water) is forced through the discharge portion of the cylinder, which is thus cleaned.

A construction of the device according to this invention is illustrated by way of example in the accompanying drawing, in which:—

Figure 1 is a side elevation of the apparatus partly in section and Fig. 2 is a section on a somewhat larger scale on line A—B of Fig. 1.

The device consists of a cylinder 1 in which a worm 2 rotates. On both sides of

the cylinder body are arranged sieves or the like 3 above which are arranged protecting segments 4 (Fig. 2) which are perforated. The worm 2 is driven by pulleys 5, 6 and by gears 7, 8. The rear end of the cylinder 1 is closed by a head 9 in which is arranged a discharge opening 10 for removing the separated stones and other impurities. The said opening can be closed.

According to the invention the discharge portion 11 of the cylinder 1 is made longer than in known devices, so that the stones and the like which have separated from the clay can collect therein. In order to remove the stones, etc., more easily, this part of the cylinder is provided with an opening 12 to which a conduit 13 can be connected, through which water can be pumped by means of a pump of any desired type through the discharge portion 11 of the cylinder 1.

What I claim as my invention and desire to secure by Letters Patent is:—

1. In a machine of the character described the combination of a stationary cylinder having perforated circumferential walls for screening the material, and also having a discharge opening in one of its heads, semi-cylindrical sieves arranged within said cylinder on both sides thereof, a collecting chamber at one end of the cylinder adjacent to and in communication with said discharge opening, a mixing and conveying worm arranged longitudinally within the cylinder, means for rotating said worm, a force pump, and a connection communicating at one end with the force pump and at the other end with the collecting chamber of the cylinder.

2. In a machine of the character described the combination of a stationary cylinder, semi-cylindrical sieves arranged interiorly of and on both sides of said cylinder, perforated protecting segments arranged at intervals longitudinally of the cylinder above the sieves, said cylinder having a discharge opening in one of its heads, a collecting chamber at one end of the cylinder adjacent to and in communication with said discharge opening, a mixing and

conveying worm arranged longitudinally within the cylinder, means for rotating said worm, a force pump, and a connection communicating at one end with the force pump and at the other end with the collecting chamber of the cylinder.

5 In testimony whereof I have signed my

name to this specification in the presence of two subscribing witnesses.

MICHAEL BOHN.
